UNITED STATES PATENT OFFICE

101,129

DESIGN FOR A WATCH BOX

Eugene Lux, New York, N. Y., assignor to The
Gruen Watch Company, Cincinnati, Ohio, a
corporation of Ohio

Application April 25, 1936, Serial No. 62,299

Term of patent 7 years

To all whom it may concern:

Be it known that I, Eugene Lux, a citizen of the United States, residing at New York, in the county of New York and State of New York, have invented a new, original, and ornamental Design for a Watch Box, of which the following is a specification, reference being had to the accompanying drawing, forming a part thereof.

In the drawing:

Figure 1 is an end elevation of a watch box, showing my new design;

Figure 2 is a side elevation thereof; and

Figure 3 is a top plan view of the watch box

all three figures showing the watch box closed;
Figure 4 is a top plan view of the watch box open;

Figure 5 is an end elevation with the watch box open;

Figure 6 is a side elevation with the watch box open.

I claim:

The ornamental design for a watch box substantially as shown.

EUGENE LUX.
